WILLIAM L. M. JONES, OF WINNIPEG, MANITOBA, CANADA

HARVESTING MACHINE

Application filed July 3, 1931, Serial No. 548,572, and in Canada July 2, 1931.

The invention relates to improvements in harvesting machines and an object of the invention is to provide a harvesting machine which will build the cut grain delivered there-
 5 to into a stack and deposit the stack firmly planted on the ground in an upstanding position, the machine being entirely under the control of a single operator attending it.

A further object of the invention is to pro-
 10 vide a machine which will build a circular stack having the heads of the grain at the centre and the butts at the outer side and will also give the stack a cone shaped top and pack the grain as the stack is being built to give
 15 a relatively firm stack.

A still further object of the invention is to provide a means which will tuck the outer side of the stack as it is being built and thereby interknitting the butt ends of the grain so that
 20 the side of the stack is firm and will resist wind.

A still further object of the invention is to provide a machine wherein the stack is built by feeding the grain in a special manner
 25 through the open top of a cylindrical container having a rotating table closing the bottom thereof, such resulting in the grain being built up in a spiralling manner within the container to form a stack with the heads there-
 30 of centrally of the stack and the butts out.

A further object of the invention is to provide the table with cleats or such like mem-
 35 bers insuring of the turning of the grain with the table and means for initially raising the container to clear the cleats prior to the container being moved back to deposit the stack.

A further object of the invention is to pro-
 40 vide a container which after the stack has been built can be moved rearwardly to de-
 posit the stack on the ground and to associate with the container, gates automatically
 45 opened to permit the stack to clear the ma-
 chine, such gates being also automatically closed and without slamming as the container moves back to its initial receiving position.

A still further object is to provide means to effectively hold the lower inner corners of the gates closed during the time that the stack
 50 is being built and for a short period after the container has started its rear movement.

A still further object of the invention is to provide opposing spaced rack bars extending centrally forwardly from the container and a driven gear which can be engaged with one or other of the rack bars by the attendant 55 to effect the rear or forward movement of the container and to arrange the rack bars in respect to the gear that when the container has reached its rear or forward position, it will automatically stop due to the gear run- 60 ning off the end of the rack bar at which time the other rack bar underlies or over- lies, as the case may be, the gear.

A still further object of the invention is to provide means whereby the table is auto- 65 matically stopped rotating when the container starts its rear movement and means whereby the packer and tucker utilized will also be automatically thrown out of com-
 70 mission when the container starts to move rearwardly and to arrange parts such that when the container has resumed its original position, the table packer and tucker will be operated.

A further object of the invention is to 75 provide a packer for the top and a tucker for the side of the stack being built in the container which will move with the container when the same is depositing the stack and will not be driven during such time and 80 to provide means for automatically driving the packer and tucker when the container resumes its normal forward position.

With the above more important and other minor objects in view which will become more 85 apparent as the description proceeds, the invention consists essentially in the arrangement and construction of parts hereinafter more particularly described, reference being had to the accompanying drawings, in 90 which:-

Fig. 1 is a front view of the machine, the stub tongue being shown in vertical section.

Fig. 2 is a plan view of the machine.

Fig. 3 is a vertical sectional view at 3—3 95 Figure 2.

Fig. 4 is a view of the inner end of the machine.

Fig. 5 is a perspective view of the ma- 100
 chine frame.

Fig. 6 is a perspective view of part of the container frame work and showing the tucker 39 and other parts associated therewith.

Fig. 7 is a perspective view of one of the gates.

Fig. 8 is a perspective view of a pair of tucker fingers.

Fig. 9 is a plan view showing one of the gates in open position and other parts associated therewith.

Fig. 10 is an enlarged detailed vertical sectional view at 10—10 Figure 2.

Fig. 11 is an enlarged detailed vertical sectional view at 11—11 Figure 2.

Fig. 12 is a horizontal sectional view at 12—12 Figure 11.

Fig. 13 is an enlarged detailed vertical sectional view at 13—13 Figure 2.

Fig. 14 is an enlarged detailed horizontal sectional view at 14—14 Figure 7.

In the drawings like characters of reference indicate corresponding parts in the several figures.

The machine embodies a main frame 1, the details of which are best shown in Figure 5. The main frame is supported at one side by a bull or master wheel 2 and at the other side by a ground wheel 3, the wheels being carried by shafts 4 and 5 suitably mounted in bearings carried by the main frame. It will be observed that the sides of the main frame are made particularly strong by effectively bracing.

Associated with the bull wheel, I provide at the inner side a relatively large chain wheel 6 and at the outer side a considerably smaller chain wheel 7, the chain wheel 6 being connected by a chain 8 to a chain wheel 9 mounted on a forward cross shaft 10. The chain wheel 9 is rotatably mounted on the cross shaft and is controlled by engageable male and female clutch members of well known design and indicated generally by the reference numeral 11, the arrangement being such that when the clutch members are engaged, the chain wheel rotates the shaft and when disengaged, the chain wheel rotates freely on the shaft.

The movable clutch member is controlled by a rocker arm 12 pivotally attached to the machine frame and having the upper end connected by an operating bar 12' to the forwardly cranked end of a rod 13 rotatably carried by the machine frame and passing horizontally rearwardly and terminating in a hand lever 13' within convenient range of the drivers platform 14 which latter is provided with a seat 15. That part of the main frame between the wheels carries a pair of cross bars 16 and 16' which support more or less centrally of their length a plate 17 which is provided with an upstanding pivot pin 17'.

This pin forms a central pivot point for a circular table 18 which is adapted to re-

move in the lowermost part of the frame, the rear edges of the table being supported by rollers 19 carried by a rearward frame cross bar 19' and the forward side of the table being carried by a pinion 20 which engages continuously with a circular rack bar 20' fastened to the under side of the table adjacent the edge thereof. A roller 21 rides the top of the table in a location adjoining the pinion, such roller insuring of the rack bar and pinion being maintained positively in mesh.

The pinion 20 is carried by the rear end of a short shaft 22 rotatably carried by the forward part of the frame and the shaft is supplied with a chain wheel 22' connected by a chain 22" to a chain wheel 23 mounted on a countershaft 23' rotatably carried by the frame and provided at its forward end with a bevel pinion 24' which meshes continuously with a bevel gear 24 rotatably mounted on the shaft 10. A clutch indicated generally by the reference numeral 25 is associated with the bevel gear and the shaft 10, one of the clutch members being driven by and slidably mounted on the shaft and controlled by a link 25' pivotally connected to a bell crank 25" carried by the frame. A pulling bar 26 is also connected to the bell crank and extends vertically upwardly and has the upper end thereof pivotally connected to a crank 27' extending forwardly from an elevated cross shaft 27 carried by the fore part of the frame structure. One end of the latter shaft is supplied with a crank 28 which is connected pivotally to an operating bar 28', the rear end of which is pivotally attached to a manipulating lever 29 pivotally carried by the rear part of the frame in a location adjoining the operator's seat.

According to this arrangement, the operator by manipulating the lever 29 can engage or disengage the clutch 25 and in so doing effect the rotation or stopping of the table. The table is provided at the upper face with a number of radially disposed cleats 18' herein shown as angle bars.

Above the table is a cylindrical casing which is indicated generally by the reference numeral 30 and this casing is carried by the frame and is adapted to move forwardly and rearwardly thereon and in its forward position forms with the table a grain receiving container in which stacks are built in a manner fully described hereinafter.

The container comprises a forward vertically disposed and suitably braced semi-cylindrical body 31, the rear part of which is normally closed by rear gates 32 and 33, one of which is shown in detail in Figure 7. It will be observed by reference to this figure that the gate is formed from vertically disposed angle bars 34 and 34' which are connected by spaced upper, lower and intermediate bowed bars 34" to which bars, the closure plate 35 is

riveted. The bars 34' are approximately the same height as the body part 31 of the container while the bars 34 are somewhat higher than the container and are pivotally connected by hinges 36 in each instance to the rear vertically disposed bars 37 of a suitably braced frame work 37' reinforcing the fore part 31 of the container.

This frame work is utilized also to support the driving mechanism of a packer 38 and a tucker 39 associated with the container and the details of which will be later described. The bars 37 extend above the body part 31 of the container and are effectively braced to the frame work as indicated at 40 and the upper ends of the bars 34 are connected by angularly disposed tie rods 41 centrally to the uppermost bars 34', such avoiding sagging of the gates.

The gates are also reinforced by crossed tie rods 42 passing diagonally across the same from corner to corner at the exterior.

The cylindrical container is supported centrally at the sides by rollers 43 and 43' which operate on rearwardly extending elevated horizontally disposed opposing tracks 44 and 44' carried by the main frame and it will be observed that the rear ends of these tracks extend rearwardly a considerable distance to the rear of the main frame, the rear ends thereof being suitably supported by angle braces 45.

The front ends of the tracks are designed to support the cylindrical container with the lower end thereof just nicely clear of the table and the tracks are provided with slight offsets 46 designed in the initial rear movement of the container to bodily lift the same so that the lower end thereof can clear over the cleats 18' of the table. Once the container has been so lifted, it moves horizontally rearwardly on the rear portions of the tracks and its rear travel is such that any stack built in the container will be cleared off the rear side of the table. The container is positively pushed rearwardly and pulled forwardly on the tracks, the time of starting the forward and backward movement being controlled by the attendant but the stopping of the forward and backward movement being automatic. The controlling mechanism will be later described in detail.

Means is provided for reinforcing the lower inner corners of the gates as the container is moving rearwardly and such embodies a somewhat V-shaped pressure bar 47 secured to the lower part of each gate and arranged to engage with a guide bar 48 permanently secured to the rear part of the frame.

Obviously these V-shaped pressure bars 47 will take any undue strain brought on the lower inner corners of the gates at the time the container is moving backwardly and will serve to reinforce the lower inner corners of the gates until such time that the said bars

47 have cleared from the out curving rear ends of the bars 48.

Means is also provided for holding the gates normally pressed closed, for opening the same to free the stack deposited on the stubble and for closing the gates after the stack has been deposited and during the forward movement of the container. Such embodies a horizontal lever 49 pivotally attached more or less centrally to the hinged side of the gate and having the rear end thereof pointed and provided adjoining the point with a suitable stop 49'. A spring 50 is interposed between the inner side of the lever and the gate and in the closed position of the gates, the rear ends of the levers are engaged with the inner faces of the tracks 44 and 44' which they ride in the back going movement of the container and normally the springs 50 are compressed so that they are acting to force the gates closed. The spring is mounted on a rod 50' having one end pivotally attached to the lever 49 and the other end passing slidably through an angle bracket 50" secured to the adjacent gate 90 and having the extremity thereof terminating in an enlarged head 50'.

Rearwardly each of the tracks is provided with means for catching the rear pointed end of the lever 49 held by that track and such embodies a horizontally disposed arm 51 having the outer end thereof pivotally connected at 51' to an outstanding bracket 52 secured to the track and the inner end terminating in an eye 53.

The rear end of the track carries a stop 54 engageable with the inner end of the arm 51 and the arm is held normally pressed against the stop by a coiled spring 51" connecting the arm to the bracket. The eye 53 is normally held by the latter spring and stop so that it will receive the pointed rear end of the lever 49 as the same moves backwardly with the container.

According to the above arrangement, it will be apparent that when the pointed ends of the levers have entered the eyes in the rear movement of the container, the stops 49' will engage the eyes and in the further rearward movement of the container, the lever arms 51 will be compelled to swing rearwardly and outwardly around their pivot points 51' and as they swing, will cause the out swinging of the levers 49 and the consequent out swinging of the gates through the rods 50', the final out swung position of one of the gates being shown in Figure 9.

It will be observed that during their opening movement and when opened, the gates are positively controlled and by considering Figure 9, it will be obvious that the gates cannot start to close until the container starts to move forwardly. In the forward movement of the container, the gates gradually close in, the arms 51 swinging back to

their normal position as shown in Figure 2 and the pointed ends of the levers 49 withdrawing from the eyes and then riding ahead in contact with the inner faces of the tracks 44 and 44'.

To the container reinforcing frame work, centrally at the front, I permanently secure two forwardly extending, spaced, parallel, horizontally disposed, relatively long bars 55 and 55' which have their forward ends connected by a vertical bar 55x.

An upper angularly disposed brace bar 56 extends between the upper end of the bar 55x and the upper part of the frame work and two angularly disposed horizontal brace bars 57 and 57' extend also forwardly from the container frame work and have their converging forward ends permanently fastened to the upper end of the bar 55x. These brace bars amply support and reinforce the forward ends of the bars 55 and 55' and it will be observed that all the latter bars move with the container. The bars 55 and 55' support opposing, horizontal lying, spaced, upper and lower rack bars 58 and 58' and it will be here observed that the forward end of the lower rack bar extends in advance of the forward end of the upper rack bar and that the rear end of the upper rack bar extends rearwardly beyond the rear end of the lower rack bar.

The main frame of the machine carries forwardly and more or less centrally thereof, upper and lower rollers 59 and 59', the roller 59 continuously riding the upper side of the bar 55 while the roller 59' continuously rides the under side of the bar 55', the bars 55 and 55' forming tracks for these rollers as well as supports for the rack bars. From the above, it will be apparent that the weight of the cylindrical container is carried by the rollers 43 and 43' operating on the tracks 44 and 44' and it is prevented from tilting as it moves backwardly and forwardly by the rollers 59 and 59' operating on the forward tracks or bars 55 and 55'.

To the shaft, I secure permanently a driving gear wheel 60 which is positioned between the rack bars and has the teeth thereof at all times clear of the rack bars. The shaft carries also a pair of rearwardly extending arms 61 and 61' which are rotatably mounted on the shaft and span the gear wheel and have their rear ends supporting a short shaft 62 on which I mount a further gear wheel 63 continuously meshing with the gear wheel 60 and positioned between the rack bars.

The gear wheel 63 is utilized for shifting the container by engagement with one or other of the rack bars as it will be apparent that one by lifting the gear wheel 63 can pass it into engagement with the upper rack bar and by lowering it can pass it into engagement with the lower rack bar. The raising and lowering of the gear wheel 63 is

controlled by the attendant from the seat 15 in the following way.

To the rear ends of the arms 61 and 61', I pivotally connect the lower ends of upwardly extending bars 64 and 64' which have their upper ends pivotally connected to similar cranks 65 and 65' extending rearwardly from the shaft 27 hereinbefore mentioned which shaft it will also be remembered controls the movement of the table 18 through the clutch 25, the arrangement being such that during the interval that the container is moving rearwardly, the table is not rotating as the clutch 25 is disengaged coincident with the up movement of the gear 63 into contact with the rack 58. It will be observed that the instant the gear 63 engages the rear end of the rack bar 58 (see Figure 3), the container will start moving rearwardly and will continue to move rearwardly till said gear runs off the front end of the said rack bar at which time the container will stop at its rearmost position, the table being inert during the rear movement of the container.

When the attendant desires to return the container to its original forward position, he will shift the lever 29 in a direction to swing the gear 63 into contact with the underlying extended end of the rack bar 58' at which time, the clutch 25 will be engaged and the table will commence to rotate.

As soon as the said gear and latter rack bar are in engagement, the container moves ahead and will continue until the gear 63 runs off the rear end of the rack bar 58' and when this occurs the container is forward in its original receiving position and the clutch 25 remains in gear so that the table continues to rotate as the stack is being built in the container.

The forward end of the main frame is supported by a comparatively heavy forwardly extending stub tongue 66 supported by a forward truck 67, the stub tongue being braced by an angularly disposed beam 68 and the machine is drawn from the truck by a tractor or draft animals.

The machine is utilized in conjunction with a further harvesting machine somewhat of the type of a binding machine which is indicated generally by the reference numeral 69, such latter machine cutting the standing grain on the field and delivering it to the elevator of the herein described machine. The inner side of the machine for cutting the grain is located at the bull wheel side of my machine and the inner side of the grain cutting machine is adjustably supported so that it can be raised and lowered and to this end, I provide my machine in a location adjoining the driver's seat with two levers 70 and 70', the lever 70 having a pulling line 71 fastened thereto which pulling line extends forwardly over a guide pulley 71' located at the

forward inner corner of my machine and has the lower end of the line fastened to the forward inner corner of the cutting machine frame. The lever 70' carries a crank 72 which is connected pivotally to a downwardly extending link 72' pivotally attached to the rear inner corner of the cutting machine frame.

According to this arrangement by manipulating the latter levers one can raise or lower the inner side of the cutting machine frame and accordingly adjust it in respect to the inclined elevator 73 supported by the main frame of my machine at the side next the cutting machine. This elevator, the structural details of which are not herein described, is designed to elevate the cut grain and discharge the same into a hopper 74 located above the container when the container is in its forward position.

The details of the hopper are not herein described and in connection with the present disclosure, it is sufficient to understand that the hopper is provided with bottom doors which can be controlled by the attendant to discharge the grain and also direct the grain when discharging either forwardly or rearwardly in regard to the container.

It is desirable to pack the grain discharged into the container and to this end the packer 38 is used which packer is rotated at the same speed as the table and rolls on top of the grain in the container, the packer being a floating one so that it can rise to accommodate the gradual filling of the container with the grain. The packer 38 also remains at all times with the container and accordingly I provide a driving arrangement which automatically becomes disengaged when the container starts moving rearwardly and subsequently becomes engaged when the container returns to its original forward position.

The packer 38 is of a frusto-conical shape as best shown in Figure 2 and it is positioned with the large end outward and the packer shaft 38' is contained in a vertical plane radial to the container and protrudes through the side of the container between a pair of vertically disposed guide bars 75 and 75' carried by the container frame work, these guiding the shaft in its up and down movement. A stop block 75* extends between the guide bars 75 and 75' and limits the down swung position of the shaft 38' in which position the under side of the packer 38 is contained substantially in the horizontal plane and is well clear of the underlying table. The packer is provided with lengthwise extending cleats 76 in the form of applied angle irons.

The forward end of the shaft 38' is connected by a universal joint of well known type 77 to the rear end of a short shaft 77' mounted in suitable bearings carried by the

container frame work and the latter shaft is supplied with a non-circular central hole 77* and has the forward end thereof flared in a funnel like manner as indicated at 78. On the main frame of the machine in a location axially aligned with the shaft 77', I provide a bearing 79 which receives rotatably a short shaft 79', the rear end of which is non-circular and slightly pointed as shown and the forward end of which is supplied with a bevel gear 79*, the bevel gear being continuously in mesh with a bevel gear 80' located at the upper end of a vertically disposed shaft 80 carried by the machine frame and having the lower end thereof fitted with a bevel gear 80* engaging continuously with a bevel gear 80* secured to the shaft 10.

According to the above arrangement, it will be apparent that when the shaft 10 is driven, the shaft 79' will be rotated and that if the rear end of the latter shaft is entered in the hole 77* of the shaft 77', the packer 38 will be driven.

Such a condition exists when the container is in its normal forward position. On the other hand, when the container is moved back to discharge the contained stack, the shaft 77' moves away from the shaft 79' so that the packer stops rotating and does not again start to rotate until the container is returned to its original position at which time, the rear end of the shaft 79' re-enters the hole 77*. It will be here noted that the universal joint 77 permits the packer 38 to rise and fall while it is being driven.

It is also very desirable to tuck the side of the stack being formed in the container to interknit the straw and this is accomplished by the tucker 39 hereinbefore mentioned and which is constructed in detail as now described.

The container frame work supports rotatably a vertically disposed shaft 81 and this shaft carries a plurality of curved fingers 81' formed in pairs as best shown in Figure 8 and suitably bolted to the shaft. The pairs of fingers extend outwardly from the shaft and are placed 90° apart and the body 31 of the container is provided with a plurality of horizontally disposed slots 82 through which the rotating fingers enter the container in the manner best shown in Figure 2.

The frame work of the container supports rotatably a horizontally disposed forwardly extending shaft 83 which has the rear end thereof provided with a bevel gear 83' continuously in mesh with a bevel gear 83* secured to the vertical shaft 81. The shaft 83 has the forward end thereof provided with a non-circular opening identical to the opening 7' and is also supplied with a funnel shaped end surrounding such opening and similar to that 78.

The rear end of the countershaft 23' is formed non-circular and is pointed in the

same manner as the shaft 79' and the arrangement of the parts is such that when the container is in its forward position, the shaft 23' drives shaft 83 and consequently the tucker 39 and such that when the container moves back, the rear end of the shaft 23' escapes from the hole in the forward end of the shaft 83 so that the tucker 39 remains inert during the backward and subsequent forward movement of the container.

The elevator driving shaft 84 is fitted with a bevel pinion 84' continuously in mesh with a bevel pinion 85 located at the upper end of an inclined shaft 85' rotatably carried by the machine frame and the lower end of the shaft is supplied with a bevel pinion 86' which is continuously in mesh with a bevel gear 86' located more or less centrally on a horizontally disposed countershaft 86 carried by the fore part of the main frame. The countershaft has the front end thereof fitted with a bevel gear 87 which meshes continuously with a bevel gear 87' secured to the main shaft 10, the result being that the elevator is driven as long as the shaft 10 is rotated.

The rear end of the shaft 86 is supplied with a chain wheel 88 which is connected by a chain 88' to a chain wheel 89' secured on the forward end of a rearwardly extending shaft 89 suitably carried by the inner side of the main frame. The chain wheel is provided with an eccentric pin 90 to which is connected pivotally a pitman 90' extending towards the cutting machine 69 and utilized for driving the cutting knives 69' of such machine. The rear end of the shaft 89 is provided with a bevel gear 91 which meshes continuously with a bevel pinion 91' located at the inner end of a relatively short shaft 92 carried by the rear inner corner of the main frame and this shaft is utilized to drive the canvas 69' of the grain cutting machine, the connections being shown in Figure 2 but not described in detail.

From the above description, it will be seen that all the various moving parts are driven by the shaft 10 and that the shaft is operated by the bull or master wheel 2, the clutch 11 being supplied so that when out the machine can move over the ground with all the moving parts described inert. This is valuable when the machine is being transported from place to place.

In order to better understand the machine, I will now describe the manner in which it operates, assuming that it is moving over the field with the grain cutting machine, with the clutch 11 engaged, the gear wheel 63 in the position shown in Figure 3 and the clutch 25 engaged. At such time, the elevator will be in operation and delivering the cut grain from the cutting machine to the hopper 74 and the cut grain will be discharging from the hopper by gravity into the container which is in its forward position with

the gates closed. The table will also at such time be rotating and the packer and tucker will be working.

The hopper is located in respect to the underlying cylindrical container that the grain is deposited in the container with the heads located centrally of the container and the butts disposed adjacent the sides of the container and here it is to be noted that the standing grain cut by the cutting machine falls with the heads to the rear of the canvas 69' thereof and will be carried up the elevator with the heads to the rear so that if the hopper be properly positioned in respect to the cylindrical container, the heads will all fall approximately in the central area of the container. As the grain is falling, the table is rotating so that the grain is laid in the container in a spiralling manner, heads in and butts out.

The grain in the lowermost part of the container is not initially packed by the packer 38 as such is not necessary due to the fact that as the height of the stack increases, the weight of the upper part of the stack will serve to press down the grain in the base thereof. As the height of the stack increases, however, the packer 38 comes into commission and presses down on the top of the building stack, it being remembered that the said packer can move up to accommodate the gradual increasing height of the stack being formed. It will also be noted that the cone shaped formation of this packer will give the completed stack a conically shaped top which is very desirable as the stack on the field will shed rain.

During the interval that the stack is being built, the tucker 39 is also working to aid the table in rotating the stack within the cylindrical container and as the tucker 39 is rotated slightly faster than the table, the fingers have the effect of tucking the side of the stack to intertwine the butts of the grain so that when the stack is subsequently deposited on the field, it will be firm and there is very little possibility of wind blowing the grain away or upsetting the stack. The fact that the heads of the grain are located centrally of the stack is also quite desirable.

When the operator considers that the stack is satisfactorily built in the container, he pulls the lever 29 in a direction which will engage the gear wheel 63 with the rack 58 which will start the container moving back and which also disengages the clutch 25 so that the table stops rotating. As the container starts to move back, it is initially raised slightly by the offsets 46 to permit the bottom of the container to clear over the cleats 18' and coincident with the initial back movement of the container, the packers 38 and 39 cease operating as the shaft 77' moves away from shaft 79' and the shaft 83 moves away from shaft 23'.

During the time that the stack is being formed, the gates are positively held shut by the springs 50 and the pressure bars 47. As the container moves back on the tracks, the pressure bars escape from the guide bars 48 and the pointed ends of the levers 49 enter the eyes 53'. The gates are then gradually opened moving out to a position to allow the planted stack to clear. At this time, the gear wheel 63 has reached the forward end of the rack bar 58 and runs off the same with the result that the container stops in its rearmost position and will stay in such position until the attendant manipulates the lever 29 in a direction which will pass the said gear wheel into engagement with the then underlying forward end of the rack bar 58'.

When this occurs, the container moves ahead to its original position, the gates being closed automatically and without slamming and held closed by the combined action of the bars 47 and the springs 50. The latter movement of the lever 29 also re-engages the clutch 25 so that the table starts to rotate when the container starts its forward movement and as the container reaches its forward position, the shafts 79' and 77' re-engage as do also the shafts 23' and 83, such resulting in the driving of the packer 38 and tucker 39. The elevator is operating continuously while the machine is working and the capacity of the hopper is such that it will hold sufficient grain to permit of the depositing of the stack.

When the machine is being moved from place to place, the attendant will manipulate the lever 13' to disengage the clutch 11 and at such time, the chain wheel 9 will rotate idly on the shaft 10 which remains stationary. Accordingly all parts driven by the latter shaft will be inert.

What I claim as my invention is:—

1. In a harvesting machine, an upstanding cylindrical grain receiving casing having rear outwardly swingable gates, stationary rear going tracks located at the sides of the casing and supporting the same for forward and back movement, a rotatably mounted platform underlying the casing in its forward position on the tracks, means for moving the casing rearwardly on the tracks and for subsequently returning the same to its original position, means for automatically opening the gates as the casing approaches its rear position and for closing the gates as it subsequently moves forwardly and means for rotating the platform.

2. In a harvesting machine, an upstanding cylindrical grain receiving casing having rear outwardly swingable gates, stationary rear going tracks located at the sides of the casing and supporting the same for forward and back movement, a rotatably mounted platform underlying the casing in its forward position on the tracks, means for moving the casing rearwardly on the tracks and

for subsequently returning the same to its original position, means for automatically opening the gates as the casing approaches its rear position and for closing the gates as it subsequently moves forwardly and means for automatically rotating the platform when the casing returns to its forward position and for automatically rotating the platform when the casing returns to its forward position and for automatically stopping the rotation of the platform when the casing starts to move rearwardly.

3. In a harvesting machine, a main frame, rearwardly extending opposing stationary tracks carried by the frame, a rotatably mounted platform located forwardly of the frame, a cylindrical grain receiving casing normally overlying the platform and having the lower end thereof closed thereby, said casing being provided rearwardly with rearwardly and outwardly swingable similar hinged gates, rollers supporting the sides of the casing from the tracks, manually controlled means for moving the casing rearwardly to discharging position and for subsequently returning the casing to its forward position, means for automatically opening the gates as the casing approaches the rear ends of the track and for subsequently closing the gates as the casing advances and means for rotating the platform.

4. In a harvesting machine, a main frame, elevated opposing rearwardly extending stationary tracks carried by the main frame, a rotatably mounted platform carried forwardly by the main frame in a location between the tracks, a cylindrical casing normally overlying the platform and provided rearwardly with similar hinged gates adapted to swing rearwardly and outwardly, rollers carried by the sides of the casing and riding the tracks, manually controlled means for moving the casing rearwardly on the tracks to discharging position clear of the platform and for subsequently returning the casing to its original position over the platform, means yieldingly holding the gates closed in the forward position of the casing and during the greater part of the travel thereof on the tracks, means for automatically and positively opening the gates as the casing approaches its rearmost point of travel and for subsequently positively closing the gates as it starts advancing and means for rotating the platform.

5. In a harvesting machine, a main frame, opposing elevated rearwardly extending stationary tracks carried by the main frame, a rotatably mounted platform carried forwardly by the frame in a location between the tracks, a cylindrical casing normally overlying the platform, rollers carried by the sides of the casing and operating on the tracks and supporting the casing for forward and rear travel, manually controlled means

for shifting the casing rearwardly on the tracks to discharging position, means for rotating the platform, grain engaging members carried by the top side of the platform and offsets formed in the tracks to raise the casing clear of said latter members when it starts its rearward travel.

6. In a harvesting machine, a main frame, opposing elevated rearwardly extending stationary tracks carried by the main frame, a rotatably mounted platform carried forwardly by the frame in a location between the tracks, a cylindrical casing normally overlying the platform, rollers carried by the sides of the casing and operating on the tracks and supporting the casing for forward and rear travel, manually controlled means for shifting the casing rearwardly on the tracks to discharging position, means for rotating the platform when the casing is in its forward position over the platform, cleats secured to the top side of the platform and offsets formed in the tracks to clear the base of the casing over the cleats when the casing starts its rearward travel.

7. In a harvesting machine, a main frame, a pair of opposing rear going stationary tracks carried by the frame, a cylindrical casing mounted on the track for forward and rearward travel, said casing being provided with similar rear gates rearwardly and outwardly swingable, rearwardly extending levers pivotally secured to the sides of the casing and normally engaging the tracks, tie members connecting the rear portions of the levers to the gates and pivoted spring pressed arms located adjacent the rear ends of the tracks and provided with eyes engageable with the levers, said arms and levers being adapted to automatically open the gates as the casing approaches its rear position on the tracks and to automatically close the gates as the casing advances from its rear position.

8. In a harvesting machine, a cylindrical grain container embodying a rotatably mounted platform and a cylindrical casing normally overlying the platform and mounted for forward and rear reciprocal movement, said casing being provided rearwardly with hinged outwardly swingable gates.

9. In a harvesting machine, a main frame, opposing elevated rear going stationary tracks carried by the frame, a grain receiving casing mounted for forward and rear travel on the tracks and embodying a forward semicircular body and rear gates carried thereby, a pair of upper and lower spaced rack bars extending forwardly and centrally from the body of the casing, the lower rack bar having its forward end extending beyond the forward end of the upper rack bar and the upper rack bar having its rear end extending rearwardly beyond the rear end of the lower rack bar, rollers carried by the frame and guiding the rack bars,

a driving gear wheel carried by the frame and located between the rack bars but clear of the same and a vertically swingable gear wheel to the rear of and continuously in mesh with the former gear wheel and manually controlled means for selectively swinging the rear gear wheel into contact with one or the other of the rack bars.

10. In a harvesting machine, a main frame, opposing elevated rear going stationary tracks carried by the frame, a grain receiving casing mounted for forward and rear travel on the tracks and embodying a forward semicircular body and rear gates carried thereby, a pair of upper and lower spaced rack bars extending forwardly and centrally from the body of the casing, the lower rack bar having its forward end extending beyond the forward end of the upper rack bar and the upper rack bar having its rear end extending rearwardly beyond the rear end of the lower rack bar, rollers carried by the frame and guiding the rack bars, a drive shaft rotatably carried by the frame and passing centrally between the rack bars, a drive gear wheel secured to the shaft and located between the rack bars and clear of the same, a gear wheel swung from the shaft, located to the rear of the drive gear wheel and continuously meshing therewith and having a diameter somewhat less than the distance between the rack teeth and manually controlled means for passing the rear gear wheel selectively into mesh with the upper or the lower rack bar.

11. In a harvesting machine, a main frame, rear going elevated stationary tracks carried by the frame, a grain receiving casing mounted on the tracks for forward and rear movement and embodying a semi-cylindrical body and rear hinged gates, a pair of upper and lower spaced parallel bars extending forwardly from the body of the casing, brace bars extending between the former bars and the casing and reinforcing the same, rollers carried by the main frame and riding the upper and lower sides of the forwardly extending bars, upper and lower rack bars secured to the latter bars, the upper rack bar having its rear end extending rearwardly beyond the rear end of the lower rack bar and the lower rack bar having its forward end extending forwardly beyond the forward end of the upper rack bar, a driving shaft passing between the rack bars, a driving gear wheel secured to the driving shaft and clear of the rack bars, a further gear wheel swung from the driving shaft, continuously meshing with and located to the rear of the former gear wheel and manually controlled means for swinging the rearmost gear wheel into contact with one or other of the rack bars.

12. In a harvesting machine, a rotatably mounted driven platform, a cylindrical grain

receiving casing normally overlying the platform, a floating cone-shaped packer contained in the casing and resting on the top of the grain therein and positioned radial to the casing and with the small end of the packer adjacent the centre of the casing and means for rotating the packer.

13. In combination, a main frame, a rotatably mounted horizontally disposed forwardly positioned platform carried by the frame, a cylindrical grain receiving casing carried by the frame and mounted for forward and rear travel in respect to the frame and overlying the platform in its forward grain receiving position, a floating cone-shaped packer positioned radial to the casing and with the small end of the cone adjacent the centre of the casing, said packer travelling with the casing and being mounted to ride the grain contained in the casing and means for simultaneously rotating the platform and the packer during the interval that the casing overlies the platform and for stopping the rotation of the packer when the casing starts its rearward travel.

14. In a harvesting machine, a main frame, a rotatably mounted horizontally disposed platform carried by the main frame, a cylindrical grain receiving casing carried by the main frame and mounted for forward and rear travel in respect to the same and embodying a semi-cylindrical body and rear normally closed gates and adapted in its forward position to overlie the platform, a frame work carried by the forward side of the body of the container, a short shaft rotatably carried by the frame work, a packer shaft connected by a universal joint to the short shaft and extending radially into the container through a slot formed in the body part thereof and terminating adjacent the centre of the container, a cone shaped packer secured to the latter shaft and having the small end of the cone adjacent the centre of the container, said packer being adapted to ride the grain discharged into the container, means for automatically rotating the platform during the interval the casing is over the platform and driving means carried by the main frame for rotating the short shaft, said driving means becoming automatically coupled with the short shaft as the casing returns to its original position over the platform.

15. In a harvesting machine, a cylindrical stack forming grain receiving casing, a rotatably mounted platform closing the lower end of the casing, means for rotating the platform and a rotary tucker protruding through the side wall of the casing and operating to tuck the side of the stack there within.

16. In a harvesting machine wherein a stack of grain is built within a receiving cylindrical casing and the stack is rotated

during the course of building within the casing, means operating through the wall of the casing for intertwining the grain forming the side of the stack.

17. In a harvesting machine wherein a stack of grain is built within a receiving cylindrical casing and the stack is rotated during the course of building within the casing, means operating through the side wall of the casing to tuck the side of the stack as the stack is being built.

18. In a harvesting machine, a non-rotary cylindrical stack forming grain receiving casing, a rotatably mounted platform closing the lower end of the casing, means for rotating the platform to rotate the stack within the casing and a rotary tucker operating through the side wall of the casing to interknit the grain at the side of the stack.

19. In a harvesting machine, a non-rotary cylindrical stack forming grain receiving casing, a rotatably mounted platform closing the lower end of the casing, means for rotating the platform to rotate the stack within the casing and a rotary tucker operating through the side wall of the casing on the stack and driven at a speed slightly faster than the speed of rotation of the platform.

20. In a harvesting machine, a non-rotary cylindrical stack forming grain receiving casing, a rotatably mounted platform closing the lower end of the casing, means for rotating the platform to rotate the stack within the casing, a rotatably mounted upwardly extending shaft located at the outer side of the casing, means for driving the shaft and tucking fingers carried by the shaft and operating through the side wall of the casing.

21. In a harvesting machine, a non-rotary cylindrical stack forming grain receiving casing, a rotatably mounted platform closing the lower end of the casing, means for rotating the platform to rotate the stack within the casing, a rotatably mounted upwardly extending shaft located at the outer side of the casing, means for driving the shaft at a speed faster than the platform and curved fingers carried by the shaft and operating on the side wall of the stack within the casing, said casing being provided with side openings to admit the fingers.

22. In combination, a main frame, a rotatably mounted, horizontally disposed, forwardly positioned platform carried by the frame, a cylindrical non-rotary grain receiving casing carried by the frame and mounted for forward and rear travel in respect thereto and over-lying the platform in its forward grain receiving position, a rotary tucker travelling with the casing and protruding through the side wall thereof and engageable with the butts of the grain contained therein and means for simultaneously rotating the platform and the tucker during the interval

that the casing overlies the platform and for stopping the rotation of the platform and the tucker when the casing starts its rearward travel.

23. In combination, a main frame, a rotatably mounted horizontally disposed forwardly positioned platform carried by the frame, a cylindrical non-rotary grain receiving casing carried by the frame and mounted for forward and rear travel in respect thereof and overlying the platform in its forward grain receiving position, a rotary tucker carried by the casing and presenting prongs extending throughout the greater part of the height of the casing and protruding therethrough and engageable with the butts of the grain being built in the casing and means for simultaneously rotating the platform and the tucker during the interval that the casing overlies the platform and for stopping the rotation of the platform and the tucker when the casing starts its rearward travel.

Signed at Winnipeg this 6th day of April, 1931.
